DOOR SPRING AND CHECK

Bonnie L. Mallory, Cleveland Heights, Ohio, assignor to The B. L. Mallory Company, Hazel Park, Mich., a corporation of Michigan

Application July 27, 1946, Serial No. 686,697

16 Claims. (Cl. 16—49)

1

This invention is an improved door spring and check. It is a modification of the combined spring and recoil retarder or shock absorber that forms the subject matter of a companion application filed concurrently herewith.

Besides the general objects, which it has in common with the invention just referred to, of providing a relatively simple and compact construction that is made up almost entirely of sheet metal stampings so designed as to cheapen and facilitate production and assembly; that is convenient of installation, and that is very efficient and durable in service, requiring little or no attention after installation, my present invention has the further objects of providing a door spring and check that offers the minimum of resistance to the opening of the door up to a certain point when it functions to slow down the movement of the door and prevent too sudden a stop when the door is swung fully open, and which offers no resistance to the action of the spring in closing the door until the door has reached a certain point when there is a progressive increase in resistance until the maximum is attained just before the door closes; of providing a door spring and check wherein the spring may be easily and quickly adjusted to produce a spring action appropriate to the weight and size of the door with which the device is to be used, and of providing a door spring and check that is quiet in operation.

A further object of my present invention is to provide a stop that is semi-automatic in its action in that by quickly releasing the door when the latter is swung to the limit of its movement through a predetermined "full open" position, the stop will function to hold the door in said position; and, reversely, when the door is again swung to the limit of its movement and slowly released, the stop will be rendered inoperative to allow the door to close.

A still further object is to provide a construction, involving the aforesaid stop, which is permanently assembled at the time of manufacture for use with either a right hand or a left hand opening door, and incapable of attachment to the other, thereby insuring against a wrong installation.

The foregoing objects and advantages, with others hereinafter appearing, are attained in the embodiments of the invention illustrated in the accompanying drawing wherein Fig. 1 is a fragmentary elevational view of a door and door frame equipped with one form of my improved door spring and check; Fig. 2 is a bottom plan

2

view of the door spring and check shown in the preceding view, drawn to a scale considerably larger than that of Fig. 1, the door and frame being indicated in the present view by dot-and-dash lines; Fig. 3 is a section on the line 3—3 of Fig. 2; Fig. 4 is a sectional detail on the line 4—4 of Fig. 3; Figs. 5 and 6 are views at right angles to each other of a plurality of energizing bands employed in the illustrated embodiments of the invention, and which are shown as straight or in relaxed condition as they would appear when not in the casing; Fig. 7 is an elevational view of a modified form of the invention incorporating a stop for holding the door open, the aspect of this view being indicated by the line 7—7 of Fig. 8; Fig. 8 is a bottom plan view of the construction shown in Fig. 7, the present view indicating the closed, open, and intermediate positions of the door, with the corresponding positions of the device indicated in full lines where the door is fully open, and in dot-and-dash lines where the door is in closed and intermediate positions, and Fig. 9 is a transverse section through the device as the parts would appear when the door is in intermediate position, the plane of section being indicated by the line 9—9 of Fig. 8.

In the drawing, the door is designated D, and it is connected, by the usual hinges, to the frame F, one of the hinges being shown at H in Fig. 2. Secured, as by screws 1, to the frame F, in the angle adjacent the top of the door next to the hinged side thereof, is a bracket 2, to which is fastened, as by welding, a cover 3 having a depending peripheral flange 4. The cover is circular and at its center is provided with an aperture which registers with one of the same size in the bracket 2, and projected through the apertures in the cover and bracket is the reduced end of a mounting stud 5. The parts are rigidly secured together, desirably by welding the reduced end of the stud to the bracket. Similarly secured within registering slots of the bracket and cover is one end of a finger 6. Surrounding the mounting stud, adjacent the cover 3, is a bushing 7, and mounted on the stud below said bushing is a bearing 8.

10. Is a cylindrical housing or casing having an annular end wall 11 that is provided with a central inwardly directed boss 12, said boss surrounding and being secured to the bearing 8. The upper edge of the peripheral wall of the casing 10 loosely fits within the flange 4 of the cover 3 so that the casing is capable of free rotation

with respect to said cover. Snugly fitted within the peripheral wall of the casing 10 is a layer 15 of suitable friction material, and expanded against the inner surface thereof are a plurality of resilient energizing bands. Three such bands are shown, and they are designated, respectively, 16, 17 and 18. Fastened to each band near one end thereof is an L-shaped abutment, those of the respective bands being designated 16^a, 17^a and 18^a. Also secured to the bands in opposed spaced relation to these abutments, are others designated 16^b, 17^b and 18^b, the latter abutments being spaced variable distances from the first mentioned abutments, the distances, according to the present illustrated arrangement being progressively greater from the band 16 to the band 18. The previously mentioned finger 6 that is carried by the stationary structure comprising the bracket 2 and cover 3 reposes within the space between the opposed sets of abutments, and in the operation of the device said finger is alternately engaged by the abutments of the opposed sets, as will more fully appear hereinafter.

Fastened, as by welding, to the outer side of the bottom of the casing 10 is one end of an arm 20. Said arm is provided with a longitudinal slot 21 having an enlargement 21^a at one end thereof, and arranged to traverse this slot is a roller 22. Said roller is mounted on a stud 23, carried by a bracket 24 that is fastened by screws 25 to the door D. The roller is shown as operating between two washers 26 and 27 which, with said roller, are loosely mounted on the stud 23 between the head thereof and the portion of the bracket 24 to which the stud is riveted. The enlargement 21^a of the slot permits passage of the washer 27 during installation.

Occupying the casing 10 and arranged substantially concentric to the axis thereof is a coil spring 30, the ends whereof are turned in an axial direction and are engaged, respectively, through registering holes in the cover 3 and bracket 2 and in the wall 11 of the casing and the adjacent part of the arm 20. There is, desirably, a series of holes 33 formed in the wall 11 and arm 20, as shown in Fig. 2, so that the tension of the spring may be adjusted by engaging its adjacent end in different ones of said holes. The parts are held in assembled condition by a screw 35 that is threaded into the lower end of the mounting stud 5 and is shown as supporting a washer that engages the lower end of the bearing 8.

Before describing the operation of the invention, I wish to say that, when the device is in normal condition—that is, when the door is shut, the abutments 16^b, 17^b and 18^b engage the finger 6, as indicated in Fig. 4. Now, upon opening the door, the arm 20, and consequently the casing 10, layer 15, and energizing bands 16, 17 and 18, swing or rotate in the direction indicated by the arrow in Fig. 4. At the same time, the tension of the spring 30 is increased because the spring is wound tighter as the door swings open. The only resistance initially imposed upon the swinging open of the door is that offered by the spring 30. However, after the door has swung open a sufficient distance to cause the abutment 16^a to engage the finger 6, the resistance will be increased by the retarding influence of the band 16. This will be relatively slight, however, because of the fact that the abutment 16^a is very near the advanced end of the band 16, wherefore the shorter or said advanced end of the band has little tendency to expand with added pressure

against the layer 15. During this time, the longer trailing end of the band, due to the drag of its terminal portion, will tend to withdraw from and reduce the pressure upon the layer 15. The resistance, however, will become somewhat greater when the abutment 17^a engages the finger 6 to arrest movement of the band 17, and again when the abutment 18^a engages said finger and stops the band 18. Thus there will be a building up of a reasonable amount of resistance as the door approaches full open position so as to avoid the door being brought abruptly to a positive stop. When the door is released, the spring 30, through its recoil action, swings the door toward closed position, at first with no resistance. However, as soon as the abutment 16^b engages the finger 6, it will arrest movement of the energizing band 16 and as a consequence, the longer end of said band will, under the action of the relatively rotating casing 10 and layer 15, tend to unwind, so to speak, and expand, thereby to exert more than normal pressure against the layer 15. This results in appreciable resistance being offered to the closing of the door. This resistance steps up proportionately as the abutments 17^b and 18^b engage the finger 6 and arrest movement of the respective bands 17 and 18. Accordingly, the recoil action of the spring 30 will be effectively checked or retarded and the door will be caused to close gently.

In describing the modification of the invention illustrated in Figs. 7 to 9, the parts thereof which are substantially the same as the corresponding parts of the above described form will be designated by the same reference characters. Now: substituted for the washer 26 of the first described embodiment, is a stop 40, shown as formed of sheet metal, having a downturned flange or abutment 41 at one end thereof. Near its other end the stop is provided with an aperture 42 that is occupied by the stud 23 and is sufficiently larger than the stud to insure free rotation of the stop on the stud. Obviously, the stop is overbalanced in the direction of said flange or abutment 41 and this causes the stop to bear with appreciable friction on the side of the roller 22 nearest said flange or abutment; and to prevent the stop from adhering to the overlying portion of the bracket 24 in case a film of oil is present between the bracket and the stop, one or the other, in the present instance the bracket, is provided with a slight projection 43. The disposition of the projection with respect to the range of movement of the stop 40 makes certain that the stop will bear with greater friction upon the side of the roller 22 nearest the flange or abutment 41.

It will be noted, also, that the bracket 24 is provided with bosses 45 (desirably formed by depressions) which serve to arrest the swinging movement of the stop 40, the stop being shown in full lines in Fig. 8 as engaged with one of said bosses 45. In this connection it may be explained that in any installation, only one of the bosses 45 is engaged by the stop 40. The purpose of the two stops is to adapt the bracket to either a right or left hand installation, so to speak, as will hereinafter more fully appear. Attention is called to another difference between the present embodiment and that previously described which is the omission of the enlargement 21^a at the inner end of the slot 21. The reason for this omission is to prevent disassembly of the structure after it is originally assembled for use with either a right hand or a left hand door, as

previously brought out. In assembling the device at the time of manufacture, the spring 30 is arranged according to whether the device is to be used with a right or a left hand door, so that the spring will tend to close the door; and the stop 40 and bracket 24 are positioned with respect to the arm 20 so that the base of the bracket will be disposed on the side of the arm adjacent the door, and the flange or abutment 41 of the stop on the opposite side of said arm. After the bracket and stop are so arranged and the shank of the stud 23 is riveted to the bracket, the parts are incapable of disassembly by any ordinary means.

In considering the operation of the present form of the invention it should be remembered that the spring tends to swing the arm constantly in a direction to close the door, so that the roller 22 always bears against the side wall of the slot 21 that is nearest the door, it being an obvious fact that the slot is slightly greater in width than the diameter of the roller. Accordingly, when the door is swung open as indicated by the arrow α in Fig. 8, the roller will rotate in a direction to swing the stop 40, by reason of the latter's frictional engagement with the side of the roller nearest the flange or abutment 41, so as to engage the advancing edge of said flange or abutment with the edge of the arm 20 remote from the door D, the parts being so indicated in the intermediate position of the door in Fig. 8. Consequently, as the door swings open, the stop 40 will slide along the arm and retain the position just described until it reaches the outer end of the arm when it will swing about said end with the flange or abutment 41 in slightly spaced relation thereto until it engages the adjacent boss 45.

At this point it would be well to interpose an explanation of how the device is installed. The mounting bracket 2 is first secured to the door frame F with the flange 4 of the cover 3 spaced approximately one eighth of an inch from the adjacent surface of the door when the door is in closed position. The door is then swung open a little beyond the location at which it is desired the door shall be held by the stop 40, and with the door held in this location the roller 22 is moved to the extreme outer end of the slot 21. With the parts so arranged, the bracket 24 is fastened to the door D by the screws 25. Before continuing to describe the operation, it should be pointed out that the distance between the rotating axis of the stop 40 and the inside surface of the flange or abutment 41 is greater than the distance between said axis and the end of the arm 20 when the door occupies the location aforesaid. Accordingly, when the door is so positioned, the abutment of the stop 40 is somewhat beyond the end of the arm 20. Now, upon quickly releasing the door to the recoil action of the spring 30, the roller 22 will recede within the slot 21 while the inertia of the stop 40 causes the stop to retain its position with the abutment 41 thereof engaged with the end of the arm so as to hold the door open. When it is desired to release the stop, the door is returned to the extreme limit of its movement and then slowly released to the action of the spring 30 under which circumstances the roller (now rotating in the reverse direction to what it did when the door was being opened) will carry the stop around slowly, so the movement of the stop will be unaffected by inertia, alongside the arm with the now advancing end of the flange or abutment 41 sliding along the

edge of the arm remote from the door until the door is closed by the spring under the ultimate cumulative constraining influence of the energizing bands 16, 17 and 18.

Having thus described my invention, what I claim is:

1. A door check comprising two members mounted for relative oscillation on substantially the same axis, the first member including a friction surface substantially concentric to said axis, a plurality of resilient energizing bands frictionally engaging said surface, circumferentially spaced opposed abutments on each band, and an element carried by the second member and overlying the energizing bands between the opposed abutments thereof.

2. A door check as defined by claim 1 wherein the abutments of the several bands are spaced apart different distances.

3. A door check as defined by claim 1 wherein the abutments of the several bands are spaced different distances from the abutment engaging portions of said element.

4. A door check as defined by claim 1 wherein said opposed abutments of each band are considerably nearer one end than the other of said band.

5. A combined door spring and check comprising the combination defined by claim 1, plus: spring means tending to effect relative rotation of said members in a direction to close a door.

6. A combined door spring and check comprising the combination defined by claim 1, plus: a spring having its respective ends connected to said members and tending to effect relative rotation of the members in a direction to close a door.

7. A door check comprising two members mounted for relative oscillation on substantially the same axis, the first member including a friction surface substantially concentric to said axis, a plurality of resilient energizing bands extending about and expanded against said surface, circumferentially spaced opposed abutments on each band considerably nearer one end than the other of said band, a finger carried by the second member and overlying the energizing bands between the opposed abutments thereof, and a coil spring having its respective ends connected to said members and tending to effect relative rotation of the members in a direction to cause the abutments adjacent the longer ends of the energizing bands to bear against said finger during the relative rotation of the members by the spring.

8. A door check comprising two members capable of relative oscillation on substantially the same axis, mounting means whereby one of said members is immovably attached to a door frame, means for operatively connecting the other member to a door hinged to said frame so that when the door is swung said other member will be rotated relative to the first mentioned member, one of said members consisting of a housing provided with a cylindrical friction surface that is substantially concentric to said axis, a plurality of energizing bands arranged side by side and extending about and expanded against said surface, circumferentially spaced opposed abutments on each band, those of the several bands being spaced different distances apart, and a finger carried by the member other than the one provided with said friction surface, said finger overlying said energizing bands between their respective opposed abutments.

9. A door spring and check comprising the combination defined by claim 8, plus: a spring connected to said members and tending to effect rela-

75

tive rotation thereof in a direction to close a door.

10. A door check comprising a cylindrical casing and a cover therefor, a layer of friction material extending about the interior of the peripheral wall of the casing, a plurality of resilient energizing bands arranged side by side and extending about and expanded against said layer, circumferentially spaced opposed abutments on each band and located considerably nearer one end of the band than the other, the several bands being arranged with their shorter ends extending in the same direction, a finger carried by the cover and overlying the bands between their respective opposed abutments, mounting means for attaching the cover to a door frame, and operative connections between the casing and a door hinged to said frame.

11. A door spring and check comprising the combination defined by claim 10 plus: a coil spring enclosed by the casing and having one of its ends connected to the cover and its opposite end connected to the casing and tending to create relative movement between the cover and casing in a direction to close a door.

12. A door spring and check comprising the combination defined by claim 10 plus: a coil spring enclosed by the casing and having one of its ends connected to the cover and its opposite end connected to the casing and tending to create relative movement between the cover and casing in a direction to close a door, one end of the spring being adjustable with respect to the part to which it is connected.

13. A door spring and check comprising a bracket that is adapted to be secured to a door frame, a mounting stud depending therefrom, a two-part cylindrical casing surrounding and substantially concentric to said stud, one part of the casing being fixed to said bracket and the other rotatable about said stud, one of said casing parts having an internal cylindrical wall characterized by a friction surface, a plurality of resilient energizing bands arranged side by side and extending about and expanded against said friction surface, circumferentially spaced opposed abutments on each band nearer one end thereof than the other, the opposed abutments of the several bands being spaced different distances apart, the shorter ends of all bands extending in the same direction, a finger carried by the other part of the casing and overlying the energizing bands between their respective opposed abutments, a coil spring surrounding the mounting stud between the same and the energizing bands, one end of the spring being connected to one of the casing parts and the other end of the spring being connected to the other casing part, an arm extending laterally of the

casing part other than the one secured to the aforesaid bracket, and operative connections between said arm and the door; the parts being so arranged that the tension of the spring is increased as the door is swung open, and the abutments nearer the longer ends of the energizing bands engage said finger during the closing of the door by said spring.

14. A device of the class described comprising two members mounted for relative oscillation on substantially the same axis, the first member including a friction surface substantially concentric to said axis, a plurality of resilient energizing bands extending about and expanded against said surface, circumferentially spaced opposed abutments on each band, a finger carried by the second member and overlying the energizing bands between the respective opposed abutments thereof, a bracket arranged for mounting on a door frame and to which one of said members is rigidly secured, an arm extending from the other member substantially radially of said axis, said arm having a longitudinal slot, a traveler occupying said slot, and a support for said traveler adapted for attachment to a door hinged to the aforesaid frame.

15. A door spring and check comprising the combination defined by claim 14 plus: spring means connected to said members and tending to effect relative rotation thereof in a direction to close the door.

16. A door check comprising two members mounted for relative oscillation on a substantially common axis, the first member including a friction surface approximately concentric to said axis, an energizing band frictionally engaging said surface, circumferentially spaced opposed abutments on said band, and an element carried by the second member and overlying the energizing band between said opposed abutments so as to be alternately engaged by the abutments during relative oscillations of the aforesaid members, the distance between the opposed abutments being considerably greater than the distance between the parts of said element wherewith the abutments are arranged to engage.
